OSCAR MARTIENSSEN, OF KIEL, GERMANY.

GAS INDICATOR.

Application filed May 15, 1924. Serial No. 713,470.

To all whom it may concern:

Be it known that I, OSCAR MARTIENSSEN, citizen of the German Republic, and residing at Kiel, county of Schleswig-Holstein, State of Prussia, have invented certain new and useful Improvements in Gas Indicators, of which the following is a specification.

This invention relates in general to gas indicators and more particularly to fire-damp or methane indicators in which a body that has been previously heated, preferably by electricity, and which acts as a catalyst and glows when brought into certain gas mixtures. The intensity with which the body glows is an approximate indication of the amount of methane contained in the air.

It is well known that certain metals such as platinum, palladium and other substances are capable of occluding light gases such as hydrogen or methane. When these metals take in these gases the volume of the latter is greatly reduced so that their absorption is accompanied by a generation of heat and consequently a heating of the occluding body. When the latter is saturated with gas no further generation of heat takes place. The heat generated is given off to the surroundings of the body and the temperature of the latter again drops to that of its environment. If, for example, a platinum wire is introduced into pure hydrogen, a brief generation of heat will take place, but only a short time elapses before the wire regains the temperature of its environment. It must be observed that this well known phenomenon is distinct from the heating process in which combustion of the occluded gases occurs when they are combined with oxygen; for if the occluding body is preheated to the temperature of ignition of the gases and sufficient oxygen is enabled to come into contact with the wire the gases occluded in the surface of the body will burn in combining with the oxygen surrounding it and this will give rise to the production of heat. As fresh combustible gas continues to flow to the occluding body and is burnt on the surface of the latter, the temperature of the body will be continually raised. This continual heating can, of course never take place in a pure combustible gas, but only in a mixture of a combustible gas and oxygen or air. The combustion will be most intensive and the temperature of the wire the great-

est when the gas mixture is such that a complete chemical conversion of the occluded gas takes place.

It has been found that this combination of the occluded gas takes place at a temperature at which the gas by itself in normal conditions does not ignite or, in other words, does not burn with a visible flame. If a suitable catalyst is used, the temperature at which the combustion commences is even lower than the temperature which gives rise to a visible incandescence of the wire.

If for example a pure platinum wire is used as a catalyst and hydrogen is mixed with the surrounding air, a combustion of the hydrogen on the wire commences at a temperature of 250° C. This is to be accounted for by the great compression of the hydrogen in the wire and the reduction of the temperature of combustion caused thereby. In the case of methane the conditions are much more unfavorable than with hydrogen partly because methane is not occluded to the same extent and is therefore not subjected to so great a compression in the wire, and partly because the temperature of ignition of methane is higher than that of hydrogen in any case. It has however been found by experiment that the catalytic body can also be made highly sensitive to methane by preparing in a certain way. This preparation consists in depositing certain rare metals of the platinum or palladium group on the wire and by making the form or structure of the deposit particularly effective by applying it in porous form. It has been found that the deposit is most favorable when it is produced by evaporating a drop of a salt solution of the rare metal on the catalytic body which may have the form of a glowing wire. To enable the occluding body to be preheated in a convenient manner it is preferably made in the form of a thin wire or fine ribbon so as to make its surface as large as possible as compared to its cross section. The preheating is accomplished best by an electric current.

When the current is regulated so that the glowing of the wire is hardly perceptible in pure air it will be found that a platinum wire placed in air mixed with hydrogen or with a mixture of hydrogen and methane of only one to 2%, will be heated to a perceptible red glow. The glow will increase

as the relative proportion of combustible gases to the air increases, and when the admixture is 10% the wire will glow at white heat.

- 5 If, however, such a heated pure platinum wire is exposed to an admixture of air and methane only, no change will occur so far as temperature of the wire is concerned. Only when the wire is prepared in the above 10 described manner, namely when certain kinds or porous metals are affixed at a number of points, the wire will assume in an air-methane mixture the same characteristics as a pure platinum wire will assume in an air-hydrogen mixture. If, for example, a loop of platinum wire is prepared as described at its crest and then preheated by an electric current so that the crest is invisible in pure air, but its limbs are just perceptible, it will 15 be found that mixtures of methane and air will cause the crest to glow much brighter than the limbs of the loop.

This peculiar behavior of a prepared wire in methane may be explained as follows:

- 20 25 The deposit of rare metal on the wire effects a partial decomposition of the methane and the liberated hydrogen is intensively absorbed by the neighboring parts of the wire and this hydrogen then burns in the wire 30 with the surrounding oxygen and heats the wire. If this heating of the wire is great enough, a combustion of the carbon separated from the methane will follow and small flames seem to form at the wire which 35 cause it to become incandescent with a white glow at these points.

Of course the wire which is thus caused to glow must not be enclosed in a totally closed chamber as in an ordinary electric glow lamp, but the external air must be allowed to pass freely to the wire. On the other hand precautions are necessary to prevent the glowing wire from effecting an ignition of the fire-damp outside of the apparatus. 40 45 This is accomplished by placing the wire in a small chamber whose walls partly consist of very pervious stones or so-called filter stones. Such stones have exceedingly fine passages which, although they allow gases 50 to pass through them, will never permit a flame to pass through on account of the low conductivity of the stone. Hence the stones act like the wire net of a "Davy" safety lamp, but they are also effective in other 55 ways; for if the gas mixture is caused to flare in the combustion chamber the flames cannot continue but must immediately go out again because the gases of combustion, viz the carbonic acid gas and steam, cannot 60 flow out through the porous stone quickly enough to prevent them from immediately suffocating the flame. Hence a continuous flame cannot arise in a combustion chamber of this kind as in a Davy safety lamp and 65 therefore the walls of the combustion cham-

ber cannot be heated so as to transfer the combustion from the chamber to the external air.

On the other hand however such stones are sufficiently pervious to gas to prevent any 70 explosion in the chamber because an explosion of a gas mixture can take place when an increase of pressure arises when the gas is ignited. On account of the great p75 perviousness of the stones a rise of pressure is however not possible and the consequence is that no sudden flaring of the entire contents of the chamber that would give rise to an explosion takes place, but the contents of the chamber gradually burn out. If, for 80 example, the apparatus is used in air containing hydrogen, then as soon as the amount of hydrogen reaches 10%, a flame will form in the combustion chamber at the wire that glows at a white heat. This flame 85 soon drops in the combustion chamber and goes out. At the same time the wire also extinguishes on account of the steam preventing a further penetration of hydrogen into the wire. Hydrogen will only commence penetrating into the wire shortly after the steam has passed out, whereupon 90 the wire is again heated to a white incandescence by the combination of the hydrogen with the surrounding oxygen. It is thus 95 seen that a flame is formed at intervals of about half a minute without any danger of gases outside the apparatus being ignited. If the admixture in the air is not hydrogen, but methane, and the wire is prepared in 100 the aforescribed manner, no flaring up of the methane mixture will as a rule occur at all because the carbonic acid gas developed at the wire prevents the combustion from spreading through the whole chamber. 105

The temperatures at which the combustion particularly of methane, occurs are very considerable and precautionary measures are therefore necessary to prevent the catalytic body from melting. This is accomplished 110 in accordance with the present invention by making the wire of an alloy of platinum and a high melting point metal of the palladium group, for instance osmium or ruthenium. Such a platinum alloy has besides 115 the advantage that the catalytic effect of the wire is materially increased. But in spite of the high melting points of these alloys further precautions are necessary to avoid the melting of the wire. These consist in using 120 a wire of suitable thickness. If the wire is very thin the effect is greatest, but the heat generated in a prepared wire at the luminous portions is so intensive that the wire would melt at these points. When the wire 125 is made thicker it conducts the heat away from the heated parts and distributes it over a larger portion of the wire and thus reduces the temperature. I have found that with a wire of a diameter of .06 to .08 mms, the 130

heating effect is still sufficiently intensive while on the other hand the heat conductance is sufficient to prevent melting of the wire under all normal conditions.

- 6 Having described the essential features of the invention I will now explain a fire-damp indicator in accordance with the invention with reference to the accompanying drawing which shows an indicator partly in vertical section so as to disclose the internal arrangement. In the drawing G is a glass vessel containing a wire W made in the form of an ordinary lamp filament except that the glass container is perforated as at 10 P and a wire which has a strong catalytic effect is employed, this wire being made of a platinum alloy of the above described character and prepared at a suitable number of points along its length in the manner 15 hereinbefore described.

The glow lamp G is fitted in the usual manner in a socket H through which current is conducted to its wire.

- 20 The glow lamp is placed in a chamber 25 formed of a cylindrical glass wall M closed at the top and bottom by very porous stones S and S'. Placed between the stones and the glass cylinder are packing rings D of asbestos. The parts M and S, S' are held 30 together by a metal mantle F perforated at the middle, the perforations serving as observation openings through which the glow wire can be observed. The lower stone S' rests on a ring Z which forms a part of a 35 base B which enables the gas mixture to enter the combustion chamber from below through holes C in the outer casing E in the direction indicated by the arrows. The glow wire receives current from a battery I placed 40 in the bottom compartment U of the apparatus. Inserted in the circuit between the battery and the glow wire is a resistance R whose electrical value is such that the current from the battery heats the wire to an 45 extent at which it is still invisible or only has a dull red glow. A regulating switch K is provided by which the resistance can be reduced to increase the current sufficiently to cause the unprepared portion of the wire to 50 glow dull red when in pure air, when the prepared parts of the wire will remain darker on account of the greater cooling surface at these parts.

- 55 When the apparatus is brought into a place in which the air contains a few percent of methane, the prepared parts of the glow wire which were previously invisible brighten up to a red hue. If the content of methane is between 4 and 8%, the not prepared parts of the wire will become white hot while the prepared parts remain red. But if the content of methane is more than 60 8% the prepared parts will remain red hot even if the current is switched completely 65 off.

The resistance R in the circuit of the glow wire is important for other reasons; for when the wire commences glowing its resistance increases and if no outside resistance were in its circuit the current strength 70 would drop and the illuminating power of the wire would be weakened. But if sufficient outside resistance is connected in the circuit, the current in the glow wire will not drop appreciably when its resistance increases so that its brightness will not be affected. 75

It follows that by selecting a suitable resistance R and a suitable length of the glow wire for a given voltage of the battery the 80 relations of the parts may be such that excessive heating and consequent melting of the glow wire is prevented.

I claim:—

1. Apparatus for indicating admixtures 85 of combustible gases and air, in particular fire damp, comprising an elongated gas absorbing body of catalytic character having a number of prepared portions distributed over its length, said portions consisting of 90 precious metal deposits of the platinum-palladium groups in porous form, means for electrically heating said body to an extent at which the not prepared portions glow just visibly when exposed to pure air, the 95 extent of the admixture of said gases to the air being indicated by increasing brightness of said glow with increasing gas percentage, the light intensity being a measure 100 for the gas percentage.

2. Apparatus for indicating admixtures 105 of combustible gases and air, in particular fire damp, comprising an elongated gas absorbing body of an alloy of platinum and a rare metal having a melting point higher 110 than that of platinum, said body having a number of prepared portions distributed over its length, said portions consisting of precious metal deposits of the platinum-palladium groups in porous form, means for electrically heating said body to an extent at which the not prepared portions glow just visibly when exposed to pure air, the 115 extent of the admixture of said gases to the air being indicated by increasing brightness of said glow with increasing gas percentage, the light intensity being a measure for the gas percentage.

3. A fire damp indicator having an 120 elongated catalytic body having deposited thereon at a number of points along its length a salt of a metal of the platinum-palladium groups, the deposit having been made when said body was sufficiently heated 125 so that the deposit was reduced to the form of pure porous metal, means for heating said body to an extent at which the not prepared portions glow just visibly when exposed to pure air, the extent of the admixture of 130 said gases to the air being indicated by in-

creasing brightness of said glow with increasing gas percentage, the light intensity being a measure for the gas percentage.

4. A fire damp indicator having a catalytic wire of .06-.08 m.m. in diameter, and composed of an alloy of platinum and a rare metal having a melting point higher than that of platinum, said wire having deposited thereon at a number of points along its 10 length a salt of a metal of the platinum-palladium groups the deposit having been made when it was sufficiently heated to reduce the deposit to a pure metal of porous form, means for heating said wire to an

extent at which the not prepared portions 15 glow first visibly when exposed to pure air, the extent of the admixture of gas to the air being indicated by increasing brightness of said glow with increasing gas percentage, the light intensity being a measure for the 20 gas percentage.

In testimony whereof I affix my signature in presence of two witnesses.

OSCAR MARTIENSSEN.
